LAURENCE O. PAINTER, OF ST. PAUL, MINNESOTA, ASSIGNOR TO PROGRAM SERVICE COMPANY, OF ST. PAUL, MINNESOTA, A CORPORATION OF DELAWARE

INTENSITY CONTROLLING SYSTEM FOR RECEIVERS

Application filed July 26, 1930. Serial No. 470,823.

My present invention relates to intensity control systems for loud speaking telephones and other receivers and more particularly to a system for controlling the potential and/or current impressed upon a receiver such as a loud speaking telephone or televiser, by the manipulation of any one of several independently operable control elements.

It is an object of my invention to provide an intensity controlling system for receivers, such as loud speaking telephones wherein the potentials impressed upon and/or the current delivered to receivers such as loud speaking telephones may be adjusted and controlled by either of two physically separated electrical intensity controlling devices, such as potentiometers.

Such a system is especially well adapted for dual volume controls in connection with a radio set. The loud speaker may be positioned in a convenient location where it can be heard from several rooms and with my system the volume may be controlled by independent manipulation of devices located in various portions of a house or building.

It is a further object of my invention to provide an intensity control system of the type described wherein two independently operable volume control devices are provided, located, if desired, at different points remote from an electrical receiving device, such as a loud speaking telephone and so connected with said receiver and a source of electrical energy such as a source of sound-carrying current that the intensity or volume produced by the receiver may be controlled within the range available by the manipulation of either one of said intensity controlling devices without requiring any manipulation of the other controlling device and wherein the intensity or volume may be reduced to zero by independent manipulation of either of said controlling devices without opening any of the circuits involved in the system or in the power supply source serving the system.

These and other objects will be apparent from the following description made in connection with the accompanying drawing

50 wherein:—

A schematic electrical diagram of a system embodying my invention is shown for use in controlling the volume of sound produced by a loud speaking telephone. It will, of course, be understood that my system is 55 equally applicable to dual control systems for regulating, from two physically separated points, the potential or current effecting electrically operated receivers or devices of various classes.

In the embodiment of the invention illustrated, a source of sound-carrying current, such as an audio-frequency amplifier T is connected with a loud speaking telephone S. Two similar intensity or volume control devices P¹ and P² are provided which may be conventional potentiometers, and through which a portion of the sound-carrying current or audio-frequency energy available at the output terminals T¹ and T² of amplifier T 70 is delivered to the loud speaker S.

The output terminal T¹ of the amplifier T is connected by means of conductor A with the terminals A¹ and A² respectively of volume control devices P¹ and P². Output 75 terminal T² of the amplifier is connected by means of conductor B to the terminals B¹ and B² respectively of the volume control devices P¹ and P². The said volume control devices include resistance or impedance elements R¹ and R² respectively which may be of equal resistances or impedances having uniform distribution of resistance or impedance between their respective terminals. This condition, however, is not essential to 85 the successful functioning of my device. As shown, resistance element R¹ has its ends or terminals connected to terminals A¹ and B¹ respectively, while resistance element R² has its ends connected to terminals A² and B² 90 respectively. The volume control devices are also provided with movable elements or contacts M¹ and M² respectively and obviously said movable elements may be adjusted to make contact with any desired points on their respective resistance or impedance elements R¹ and R². Movable element M¹ is connected with a terminal C¹ which is connected by means of conductor X with terminal S¹ of the loud speaking telephone S. 100

Element M^2 is connected with the terminal C^2 which is connected with terminal S^2 of the loud speaking telephone by means of a conductor Y .

5 The audio frequency potential existing between the terminals T^1 and T^2 of the audio frequency amplifier T also exists between the terminals A^1 and B^1 of volume control device P^1 and between the terminals A^2 and B^2 of volume control device P^2 due to the connections previously described.

10 Assuming that the resistances or impedances of the two elements R^1 and R^2 are equal and that the distribution of resistance or impedance between points A^1 and B^1 and between points A^2 and B^2 is similar, it then follows that no potential exists between corresponding points on the resistance or impedance elements R^1 and R^2 of the two volume control devices and that audio frequency 15 potentials do exist between non-corresponding points on the said elements R^1 and R^2 . With the same assumptions, it follows that the potential existing between non-corresponding points of said elements R^1 and R^2 is substantially proportional to the distance 20 between the point selected on one resistance or impedance element and the point on that same resistance or impedance element which corresponds with the point engaged by the 25 movable contact on the other resistance or impedance element. The same results can be obtained of course if resistance elements R^1 and R^2 are of unequal resistances and even though the resistance throughout the lengths 30 of the respective elements is not distributed uniformly.

35 Since the movable elements M^1 and M^2 of the volume control devices P^1 and P^2 can be brought into contact with any desired points on the resistance or impedance elements R^1 and R^2 respectively of the volume control devices P^1 and P^2 it is apparent that various portions of the audio frequency potential 40 available at the terminals T^1 and T^2 of the audio frequency amplifier A can be caused to exist between the movable elements M^1 and M^2 of the volume control devices and that the potential existing between the said 45 movable elements is transmitted to the terminals S^1 and S^2 of the loud speaking telephone S . It is then apparent that a change in the position of the movable element of either one of the volume control devices will 50 result in a change in the audio frequency potential impressed on the coil of the loud speaking telephone S and will therefore cause a change in the volume or intensity of sound produced by the said loud speaking 55 telephone.

60 It will also be apparent that when the movable elements M^1 and M^2 of the volume control devices are positioned similarly with respect to impedance elements R^1 and R^2 that zero potential will be impressed upon the loud

speaker S and no sound will be produced. With my device therefore either one of the volume or intensity controlling devices may be manipulated independently to a position where it will be matched with the particular 70 position of the other volume control device to shut off the loud speaker and cause zero potential to be impressed thereon.

75 From the foregoing description it will be seen that I have invented an extremely simple but highly efficient system for conveniently controlling the intensity of loud speakers, televisors and other electrically operated receivers. It will further be seen that the invention is equally applicable to control currents delivered to electrical receivers and it is expressly understood that I do not limit myself to the particular use of my system or to the embodiment for volume control illustrated 80 in the drawing.

85 It will, of course, be understood that various changes may be made in the form, details, proportions and arrangement of the parts, without departing from the scope of applicant's invention, which, generally stated, consists in a device capable of carrying out the objects above set forth, and in the novel parts and combinations of parts disclosed and defined in the appended claims.

90 What is claimed is:—

95 1. In an intensity controlling system for receivers such as loud speaking telephones or televisors, a source of sound or image carrying current, a receiver, a pair of physically separated independently controllable electrical intensity controlling devices each having an impedance element, a connection between one of the terminals of said source of current and one of the terminals of each of said impedance elements, and a connection 100 between the second terminal of said source of current and the other terminal of each of said impedance elements, and connections between said receiver and said intensity controlling devices whereby potential impressed 105 upon said receiver may be varied or made zero by manipulation of either of said intensity controlling devices.

110 2. In an intensity controlling system for receivers such as loud speaking telephones or televisors, a source of sound or image carrying current, a receiver, an independently controllable potentiometer, a second independently controllable potentiometer located at a point remote from said first mentioned potentiometer, electrical connections between said source of current and said potentiometers for impressing upon each of said potentiometers a potential, and electrical connections between said receiver and said potentiometers 115 whereby potential impressed upon said receiver may be varied by independent manipulation of either of said potentiometers.

120 3. In an intensity controlling system for receivers such as loud speaking telephones

or televisor, a source of sound or image carrying current, a pair of electrical conductors connected to said source, an independently controllable potentiometer, a second independently controllable potentiometer located at a point remote from the first mentioned potentiometer, each potentiometer comprising a resistance element and a contact element adjustably engaged with said resistance element, the ends of each resistance element being connected respectively to the conductors of said pair, and a receiver, the two terminals of said receiver being respectively connected to the contact elements of the two potentiometers.

15 In testimony whereof I affix my signature.
LAURENCE O. PAINTER.
